UNITED STATES PATENT OFFICE.

EMMIT G. LATTA, OF FRIENDSHIP, N. Y., ASSIGNOR, BY MESNE ASSIGNMENTS,
TO THE POPE MANUFACTURING COMPANY, OF PORTLAND, ME.

VELOCIPED.

SPECIFICATION forming part of Letters Patent No. 360,101, dated March 29, 1887.

Application filed February 12, 1886. Serial No. 191,735. (No model.)

To all whom it may concern:

Be it known that I, EMMIT G. LATTA, of Friendship, in the county of Allegany and State of New York, have invented new and useful 5 Improvements in Velocipedes, of which the following is a specification.

This invention relates to that class of machines which are provided with a front steering-wheel and a rear driving wheel or wheels, 10 and has for its object to produce a machine which is especially adapted for use on hilly or rough roads, and which can be used by riders who are unable to mount the ordinary bicycle; also, to construct a machine in which the danger of forward falls is prevented, and in which the rider can readily and quickly dismount on either side, or in front or in rear of the machine, without danger of becoming entangled with the machine.

15 The invention consists of the improvements in the construction of the machine, which will be hereinafter fully described, and pointed out in the claims.

In the accompanying drawings, consisting 20 of three sheets, Figure 1 is a fragmentary side elevation of my improved machine. Fig. 2 is a sectional front elevation of the machine. Fig. 3 is a sectional elevation of the steering mechanism and connecting parts on an enlarged 25 scale. Fig. 4 is a horizontal section on line $x-x$, Fig. 3. Fig. 5 is a side elevation of a modified construction of my improved machine.

Like letters of reference refer to like parts in the several figures.

30 A represents the driving-wheel, and A' the steering-wheel, which is arranged in front of the driving-wheel A.

a represents the axle of the driving-wheel, and b a sprocket-wheel secured to the axle of 40 the driving-wheel.

C represents the crank-shaft, which is arranged in front of the driving-wheel and provided with a sprocket-wheel, c, which is connected with the sprocket-wheel b on the axle 45 of the driving-wheel by an endless chain, c'.

D are the pedals secured to the crank-arms d of the crank-shaft in the usual manner.

E represents the rear fork or frame of the machine, which straddles the rear wheel and 50 extends forwardly and downwardly from the

axle or hub of the driving-wheel to the rim. The crank-shaft C is journaled in bearings f, which are secured to the rear fork, E, by clips f' and bolts f''. The crank-shaft C can be readily adjusted by loosening the bolts f'' and 55 sliding the clips f' on the fork-arms E.

G represents the front fork - arms, which straddle the front or steering wheel, A', and which extend rearwardly and upwardly from the axle of the front wheel and downwardly to 60 the rim, and terminate outside of the rim in a steering-head, H.

I represents the center spindle, seated in the head H and provided with a flat neck, I', which is attached to the rear fork-arms, E. 65 The head H may be of any suitable form, but I prefer the usual cylindrical form of steering-head, having an opening, h, in its rear side to admit the spindle I, and through which the neck I' of the spindle passes. The spindle I 70 is provided with upper and lower centers of the usual form, on which the steering-head turns. The ends of the steering-head are provided with internal screw-threads, which receive the screw-nuts J J', which latter are provided with conical seats j j', which form the bearings for the centers of the spindle I. The screw-nuts J J' are provided with a central bore or oil-duct, k, which extends through the screw-nuts, for oiling the centers of the spindle. 75 The oil-ducts k are closed by a screw, k', which retains the oil in the openings and prevents dust, &c., from entering the openings.

The center bearings, J J', are of different lengths, and are interchangeable, and permit 80 the spindle to be adjusted up or down in the steering-head to change the relative position of the various parts of the machine, as well as to permit the adjustment of the bearings when worn and their renewal. The bearings J J' 85 are held in position, when adjusted, by jam-nuts k''. The steering-head H is preferably arranged at an angle or incline, with its lower end slightly forward under the rear of the steering-wheel, whereby the steering-wheel is 90 rendered less liable to swerve when striking an obstruction, and the center bearings are brought closer to the center of the steering-wheel than if the steering-head were arranged in a vertical position, which enables the rider 95

to control the steering easier and causes the steering-wheel to incline toward the side it is being turned, and is less liable to buckle the wheel or loosen the tire.

5 By arranging the steering-head below the center of the steering-wheel the steering of the machine is rendered much easier than when the steering-head is arranged above the center, as the rider's weight tends to keep the 10 wheels in line; and by locating the steering-head between the wheels enables the steering to be effected with less deflection of the steering-wheel, as the rear wheel is also deflected in the opposite direction nearly as much as 15 the steering-wheel is deflected, causing the two wheels to run closer to the same line.

The neck I' of the spindle fits closely between the extensions L of the rear fork-arms, and is pivoted thereto by a bolt, l , which passes 20 through the lower end of the neck and the lower front end of the extension L .

l is a bolt which passes through the upper end of the fork-extensions L , and through a slot, m , formed in the neck I' .

25 N are arms formed at the lower ends of the fork-extensions L , and extending backwardly from the pivot-bolt l .

O represents a lever which is secured at its lower end between the arms N by a bolt, n , 30 and which extends upwardly and forwardly, so as to clear the pedals on the crank-shaft.

P represents a curved spring secured at its upper end to the neck I' , above the slot m , by a bolt, p , and at its lower end to the lever O by 35 a bolt, p' , the curved portion of the spring passing between the forward ends of the rear fork-arms, E .

R represents the handle-bars secured to the front forks, G , and extending outwardly and 40 upwardly to a convenient height, at which they are provided with outwardly-projecting handles r . The handle-bars R are preferably detachably connected with the fork-arms G , or they may be riveted or brazed thereto. The 45 lower horizontal portions, r' , of the handle-bars form convenient foot- rests, upon which the rider can rest his feet when coasting down hill, and from which he can easily replace his feet on the pedals when necessary, or jump to 50 the ground in case of a fall, the free open space between the handle-bars permitting the rider to dismount from the machine and pass between the handle-bars.

S represents a mud-guard, secured at its lower 55 end to the rear fork or frame of the machine and extending upwardly in front of the driving-wheel, and connected at its upper end to a brace, S' , which extends backward to the hub of the driving-wheel. The guard S is made 60 of tubing, and is formed to encircle the front and sides of the driving-wheel tire, as shown in Figs. 1 and 3. The upper end of the guard S terminates in a tubular socket, s , which forms a support for the saddle. The latter is fastened to a rod, s' , which is secured in the socket s by a split ring, s'' , and screw-bolt s''' .

Upon mounting a hill the rider depresses the lever O with his toe, which he can readily do without removing his foot from the pedal, until the bolt p' , which connects the lower end 70

of the spring P with the lever, is moved past a line drawn between the pivot-bolt n of the lever and the bolt p , which connects the upper end of the spring with the neck I' . When the lower end of the spring has moved past this point, the lever is forced downward by the spring, which causes the fork-extensions L to swing on the pivot-bolt l of the neck, and the upper portions of the neck and fork-extensions are brought closer together, the bolt l sliding 80 in the slot m in the neck. This movement of the spring and lever changes the position of the front and rear forks, and causes the saddle to be thrown slightly forward, so that the rider can assume about the same position over 85 the pedals when on an upgrade as when on a level road, and also by the same movement the handle-bars are thrown slightly backward of their normal position and nearer to the saddle, which enables the rider to lift on the handles, 90 if he desires. When level or descending ground is reached, the parts are readily returned to their former position by pressing forward on the handle-bars or foot-rests. If desired, the saddle may be tilted forward in hill-climbing 95 by slotting the rear ends of the braces S' , as shown in Fig. 6. In this construction the braces are sprung slightly, to cause them to bind on the bolts which secure their rear ends to the fork-arms. 100

The driving-gear and saddle being located between the points where the two wheels rest on the ground, equalizes the vibration or jar when passing over rough roads and renders it much easier to the rider. Any jar or shock 105 received by either wheel is lessened by the spring P , which forms a connection between the front and rear forks of the machine.

Constructing the frame of the machine as 110 described, and arranging the driving mechanism between the driving-wheel and the steering-wheel and below the axles of the wheels, enables the machine to be easier balanced and permits the rider to dismount from either side of the machine, as there is no obstruction between the wheels above the driving-gear. The open space between the handle-bars also permits the rider to dismount in front and pass between the handle-bars, or the rider can readily dismount in the rear without danger of entangling himself with the machine. This construction of the frame also permits the wheels to be brought very close together, if desired, as the rear part of the steering-wheel does not swing across the line of the frame, as in other 115 machines, thus making a very short machine. 120

T represents the brake-lever, which is pivoted to the rear fork-arms at t , and extends upward outside of the mud-guard, and provided at its upper end with a broad flat head, 130 t' , which projects outward on each side of the mud-guard S .

t² is the brake-spoon formed at the lower end of the brake-lever and below the rear fork-arms. Upon pressing forward on the head *t*, with either foot the brake is applied below the driving-gear, where it causes dirt or mud on the tire to fall to the ground without coming in contact with the machine. The head *t*, when pressed forward in position for use, forms a broad hollow bearing for the foot.

5 The brake-spoon is held away from contact with the tire of the wheel when not in use by a suitable spring secured to the brake-lever between the fork-arms.

10 I claim as my invention—

15 1. In a velocipede, the combination, with a front steering-wheel and a rear driving-wheel, of a frame connecting both wheels and depressed between said wheels, a driving-gear attached to the depressed portion of the frame between

20 the steering and driving wheels, and handle-bars attached with their lower ends directly to the fork-arms of the steering-wheel and having their upper portions separated from the fork-arms by intervening spaces, substantially

25 as set forth.

2. The combination, with the front steering-wheel and rear driving-wheel, of a frame connecting both wheels, and a backwardly-inclined steering-head arranged in rear of the

30 steering-wheel and below the center thereof, whereby the tendency to swerve upon striking an obstruction is greatly lessened, substantially as set forth.

35 3. The combination, in a velocipede provided with a front steering-wheel and rear driving wheel or wheels, of a pivoted frame supporting the front wheel, and two independent handle-bars connected to the front frame and extending outward and upward from the frame, substantially as set forth.

40 4. The combination, in a velocipede provided with a front steering-wheel and rear driving wheel or wheels and a connecting-frame, of two handle-bars connected to the frame and bent outward from the frame to form foot-rests and upward to form handles, substantially as set forth.

45 5. The combination, with the steering-head and spindle, of the center bearings, *J J'*, seated in threaded openings formed in opposite ends of the steering-head and made interchangeable and of different lengths, substantially as set forth.

50 6. In a velocipede, the combination, with the front steering-wheel and a rear driving-wheel and a connecting-frame, of a saddle-support pivoted at its lower end to the frame and sup-

ported at its upper end by braces *S'*, which extend rearwardly from the saddle-support and connected at their rear ends to the frame, substantially as set forth.

7. In a velocipede, the combination, with a front steering-wheel and a rear driving-wheel, of a connecting-frame composed of two parts attached, respectively, to said wheels and connected by a hinge-joint, and a spring, *P*, also connecting both parts of the frame, substantially as set forth.

8. In a velocipede, the combination, with a front steering-wheel and a rear driving-wheel, of a frame connecting said wheels and composed of two parts attached together by a hinge-joint, a saddle supported on one part of the frame, and mechanism, substantially as described, whereby the two parts of the frame are adjusted toward and from each other, thereby throwing the saddle forward or backward, substantially as set forth.

9. In a velocipede, the combination, with a front steering-wheel and a rear driving-wheel, of a jointed frame connecting the steering-wheel with the driving-wheel, handle-bars secured to the frame, and mechanism, substantially as described, whereby the handle-bars are thrown backward or forward, substantially as set forth.

10. In a velocipede, the combination, with the front fork-arms supporting the steering-wheel and handle-bars and the rear fork-arms supporting the driving-wheel and saddle, of the steering-head and spindle connecting the front and rear fork-arms, a spring, *P*, attached to the rear forks and the neck of the spindle, and a lever, *N*, whereby the position of the fork-arms is adjusted and the handle-bars and saddle adjusted toward each other, substantially as set forth.

11. In a velocipede, the combination, with the front fork-arms supporting the steering-wheel and the rear fork-arms supporting the driving-wheel and saddle, of the steering-head and spindle connecting the front and rear fork-arms, a crank-shaft attached to the rear fork-arms, and a lever arranged close to the crank-shaft, whereby the position of the fork-arms and saddle is adjusted by the rider's foot without removing the foot from the pedal, substantially as set forth.

Witness my hand this 6th day of February, 1886.

EMMIT G. LATTA.
